METHOD OF BURNING FUEL

Original Filed March 19, 1924

UNITED STATES PATENT OFFICE

JAMES W. FULLER, OF CATASSAUQUA, PENNSYLVANIA, ASSIGNOR, BY MESNE ASSIGNMENTS, TO FULLER LEHIGH COMPANY, A CORPORATION OF DELAWARE

METHOD OF BURNING FUEL

Application filed March 19, 1924, Serial No. 700,199. Renewed August 22, 1931.

This invention relates to the art of burning pulverulent fuel, and more particularly to the use of a finely divided fuel of low volatile content for heating chambers of considerable length through or along which the products of combustion pass to a stack. The principles of the invention are capable of utilization in various ways, but are of especial importance in connection with the burning of cement in rotary kilns, such as are in general use, although the application of these principles to the heating of dryers and other similar devices is also advantageous. In order that the invention may be clearly understood, its use in connection with the production of Portland cement will presently be explained although it is to be understood that the description of that adaptation is merely typical of various applications.

It is well known that considerable saving in the cost of the production of Portland cement could be made if it were possible to use low volatile fuels for firing the kilns. Attempts have been made heretofore to make use of fuel such as anthracite, culm or coke-breeze, but when the ordinary burning equipment is used for this purpose it has been found that the capacity of the kiln is materially reduced. In such kilns the three zones of dehydration, sintering, and clinkering must have a definite relation to each other in order to produce cement at the greatest kiln efficiency and when such fuels as above referred to are used without alteration in the burning equipment, it has been found that the zone of high temperature is thrown far back into the kiln. This, of course, reduces the length of the zones of lower temperature and necessitates that the kiln be run at a low speed. Also the fuel is not used to the best advantage, since the stack gases leave at unusually high temperatures. Various attempts have heretofore been made to solve the problems involved but without pronounced success. For instance, it has been proposed to make use of a mixture of bituminous coal with a small proportion of low volatile fuel. The result of burning this mixture is to some extent satisfactory, but the practice is not com-

mercially useful because of the inconvenience and labor involved in producing the mixture and also because of the relatively small saving which is secured.

The present invention, however, provides a method and apparatus by which fuel having a low volatile content may be used in such kilns in the pulverulent condition without admixture, and according to this method, the first stage of the combustion of the fuel takes place in a preliminary combustion chamber from which the ignited stream passes into the kiln. This chamber is located at the discharge end of the kiln and partially encloses the latter. The clinker discharged from the kiln passes into the chamber which may be provided with an inclined wall over which the clinker moves by gravity, or else with a traveling grate which serves to continuously remove the clinker discharged into the chamber. One of the great difficulties involved in making use of this low volatile material is the ignition of the entering fuel and the maintenance of combustion, and in the present instance this difficulty is overcome by directing the entering jet of fuel into the chamber in such a direction that the ignited stream leaving the chamber and entering the kiln makes an abrupt change of direction, resulting in a partial counterflow of the ignited stream. This returning jet or flame gives up heat to the entering fuel jet thus serving to ignite it, and also assisting in its combustion. A part of the air necessary for combustion enters with the fuel but the greater part enters the chamber along that surface over which the clinker discharged from the kiln moves. The air so entering is led close to the surface of the clinker so as to preliminarily raise the air to a high temperature and the air thus preheated mingling with the fuel in the chamber supports combustion and is carried into the kiln with the ignited stream. The turning back of the jet upon itself occurs in proximity to the clinker which is, of course, at an extremely high temperature and the entering fuel jet not only takes up heat from the ignited stream but also receives heat radiated from the moving bed of clinkers. This arrangement of the apparatus not only

increases the speed of combustion so that its first stage takes place before the gases enter the kiln proper but it further insures that the entering fuel will be continuously ignited 5 and combustion maintained. Furthermore, the zone of highest temperature is now maintained just within the discharge end of the kiln so that continuous operation with low volatile fuels is carried on without reducing 10 the capacity of the kiln, the zones of which have the relative length required for efficient operation.

In one form of apparatus which I have devised for the practice of the method, I make 15 use of a combustion chamber having a floor sloping downwardly away from the discharge end of the kiln so that the discharged clinker will pass over this floor by gravity. The fuel is projected into the chamber by 20 means of a vertical nozzle directing a jet of fuel downwardly along the side of the chamber farthest from the end of the kiln. The fuel so introduced in the chamber travels along a path which brings it close to the surface 25 of the bed of clinker and then causes it to turn upwardly and travel with a partial counterflow into the open end of the kiln. In this partial counterflow, heat is transferred from the ignited stream to the entering 30 jet which also receives heat radiated from the bed of clinker. The chamber has an air inlet located just above the floor over which the clinker is passing in the wall opposite to that into which the end of the kiln projects, 35 and the air entering the chamber is, therefore, preheated and raised to a high temperature by means of the heat contained in the clinker. Air may be introduced with the fuel both by 40 projecting into the chamber mingled fuel and air through the nozzle and also by introducing air into the chamber around the outside of the nozzle, this air being drawn into the chamber by the induction effect of the entering fuel.

45 In another form of the apparatus I provide a similar chamber having a fuel jet similarly placed. The floor of the chamber, however, consists of a traveling grate which serves to positively remove the clinker and 50 permits of making use of the apparatus under conditions where space would not be available to permit of inclining the floor of the chamber at a sufficient angle to secure the desired rate of flow of the clinker. In addition to the vertical jet I provide one or more horizontal jets the nozzles for which are adjustable so that the point of impingement of the several jets may be located as may be desired with reference to the end of the kiln. 55 These several jets are located out of line vertically and preferably the jets will not impinge until just before entering the kiln. When a horizontal burner is used the amount of fuel admitted by the two burners will be varied so as to obtain the best results, the

vertical jet serving as a pilot flame for the horizontal jet. It is also possible to make use of a low volatile fuel in one and a high volatile fuel in the other, the high volatile flame again serving as a pilot for the low volatile fuel. In this case, as before, the vertical jet is so directed into the chamber as to necessitate its partial counterflow in passing into the end of the kiln and the ignited stream in this partial return gives up a part of its heat and assists in igniting and maintaining the combustion of the entering fuel. 70

75 It will also be seen that in directing the jet downwardly in the manner described, its full force is not directed against any single surface of the combustion chamber. Although the jet is directed toward the bed of clinker, it does not impinge against this bed with full force on account of the counterflow before it enters the kiln. This jet, therefore, can do little injury to the combustion chamber and when the horizontal jets are used they are adjusted so that the fuel is projected from them directly toward the open end of the kiln. 80

85 In the accompanying drawing there is illustrated that embodiment of the invention which is now preferred, together with a modification.

90 Fig. 1 is a vertical cross-sectional view, mainly diagrammatic, showing the end of the kiln and the combustion chamber in which a single fuel jet is employed, 95

95 Fig. 2 is a view similar to Fig. 1 but showing the use of vertical and horizontal jets, 100

Fig. 3 is a horizontal cross-sectional view on the line 3—3 of Fig. 2.

105 Referring now to this drawing the kiln 4 with which this apparatus is illustrated is of the usual cylindrical type, consisting of a steel cylinder suitably lined with a refractory material. This cylinder is mounted so as to have a slight downward pitch and is mounted on bearings so that it may be rotated, thus causing the gradual movement of the material from one end to the other. The mounting and driving mechanism of the kiln is not illustrated and is of the well-known form ordinarily used for this purpose. At the discharge end of the kiln there is constructed a preliminary combustion chamber 5 which is preferably built of fire brick in any convenient manner. This chamber has an opening 6 in one side through which the end of the kiln projects and the chamber is given a sloping floor 7 so that the clinker 8 discharged from the kiln into the chamber will flow by gravity over this floor and eventually be discharged into a trough 9, whence it is removed by a traveling bucket elevator 10. The discharge end of the kiln enters the chamber at some distance above the adjacent end of the sloping floor, so that the material discharged may acquire initial velocity before it strikes the inclined sur- 110

115

120

125

130

face. The wall 11 of the chamber opposite the end of the kiln has an inlet port 12 through which air may be admitted, and this port is so located that the air enters the chamber close to the surface of the clinker so as to be preliminarily heated thereby, the admission of air through this port being controlled by slides 13 which may be operated from the platform 14. The front wall of the chamber is also provided with additional air ports 15 and 16, which may be controlled by slides and the slide 15 is provided with an observation door so that conditions within the chamber may be readily ascertained. In the top wall of the chamber is an aperture 17 into which projects a burner nozzle 18. The aperture 17 is located near the front wall and air may be admitted to the chamber through the aperture around the nozzle, the amount of air so admitted being controlled by a slide 19 encircling the nozzle. The jet of fuel projected into the chamber by means of the nozzle passes downward vertically along the front wall, as indicated at 20, and then returns upon itself as at 21 to enter the kiln. It will be noted that at its lowest point the jet flows in proximity with the bed of clinker and ignition of the entering fuel is brought about and the combustion of the jet is maintained in part by heat transferred from the ignited stream 21 in its partial counterflow and in part by heat given off by the bed of clinker.

With this arrangement low volatile fuel may be used in connection with the usual type of rotary kiln without reducing its efficiency since the fuel passes through its first stage of combustion in the chamber and by the heat absorbed from the ignited stream and also from the moving bed of clinker its ignition and combustion are continuously maintained. The zone of high temperature in the kiln lies close to its discharge end and does not extend an undesirable distance into the kiln, thus permitting of the maintenance of sintering and dehydration zones of the proper relative length and also cutting down the temperature of the stack gases.

In Fig. 2 there is illustrated a somewhat modified form of the apparatus, utilizing the principles of this invention; this is particularly suitable under conditions where lack of space prevents the use of a chamber having an inclined floor over which the bed of clinker moves by gravity alone. In this form the chamber 5 has the aperture 6, as before, into which the end of the kiln 4 projects. The inclined floor of the kiln as used in Fig. 1, however, is now replaced by a traveling grate 22, which may be of any convenient form, preferably of the endless type so that on its return to the kiln it may pass through a body of water as at 23 and be cooled so as to prevent its rapid deteriora-

tion. This grate discharges the clinker, as before, into a horizontal trough 9.

The chamber has a vertical burner 18 extending through an aperture 17 provided with air control slides 19, and is also provided, as before, with an air inlet 12, which causes the air to be admitted to the chamber in proximity to the bed of clinker traveling alone on the grate. The front wall of the chamber is also provided with an intake 15 as before, which is provided with a control slide and a similar slide 13 is provided for use in connection with the intake 12.

Located in the front wall of the chamber 11 are horizontal burners 24 here illustrated as being two in number and disposed to either side of the vertical burner 18. These horizontal burners are mounted to extend through apertures 25 provided with air control slides 26 as in the case of the vertical burner, and are adjustably mounted so that the horizontal jets may be caused to impinge on the vertical jet at any desired point.

In Fig. 3 this impingement is shown to take place just before the jets enter the kiln and this is the desired arrangement when low volatile fuel is being used in all the jets. With the jets so arranged the vertical jet is, as before, caused to counterflow partially and it gives up heat to the fuel entering through the vertical burner as well as through the horizontal burners, thus bringing about ignition and maintaining combustion of the fuel so introduced. The fuel entering from the horizontal burners also takes up heat radiated from the traveling bed of clinker, a part of which heat is also absorbed by the fuel projected into the chamber by means of the vertical jet.

The arrangement above described is the one preferred when low volatile fuel is being used in both horizontal and vertical burners, and the division of fuel between the burners may be varied at will to obtain the best results, the vertical jet serving as a pilot flame for the horizontal jet. If desired, however, low volatile fuel may be used through one burner and high volatile fuel in the other, in which case the high volatile flame acts as a pilot for the low volatile jet. It will be seen that the use of a separate pilot jet of high volatile fuel differs from the processes previously attempted since the two fuels are not mixed together, but are simply used in separate burners with the jets so projected into the chamber as to bring about the ignition and to maintain the combustion of the low volatile material being used. It is, therefore, not necessary to determine accurately the relative amounts of high and low volatile fuels to be burned prior to their ignition, but a sufficient quantity of the high volatile material will be employed so as to produce a pilot flame which is effective and

this adjustment may be made without difficulty.

It will be seen then, that I have provided a method and apparatus for the burning of low volatile fuel in the finely divided state which offers many advantages and economies. By the application of the principles of the invention, I may heat cement kilns or other similar devices at little expense, since I may use low cost materials heretofore found unsatisfactory for such use. Furthermore, the combustion of these materials is brought about under such conditions that the efficiency of the kiln is not reduced by reducing the length of the various zones in it, this being a result of the arrangement of the apparatus such that the preliminary stages of the combustion occur before the ignited stream enters the kiln. This latter feature promotes economy by reason of the fact that the temperature of the stack gases is kept low so that the amount of heat so lost is reduced. Also, since the air admitted to the combustion chamber is passed over the bed of clinker in proximity thereto, the air is preheated before it mingles with the stream of fuel, and a part of the heat absorbed by the clinker is thus made to serve a useful purpose. Another part of this heat radiates from the clinker and helps to ignite and maintain the combustion of the entering fuel stream. Since no part of the ignited stream impinges directly on a wall of the combustion chamber, the frequency with which the refractory material of the chamber need be replaced is lessened and this cuts down the cost of maintenance.

I claim:

1. The method of burning fuel for heating non-combustible material in a kiln having an inlet end for the material to be treated and a discharge end, and a primary combustion chamber in direct communication with the discharge end, which comprises passing the material through the kiln and through the primary combustion chamber and during such movement of the material heating it by the combustion of pulverulent fuel of low volatile content, the combustion taking place partly in the chamber and partly in the kiln as the gases flow from the chamber into the kiln, and confining the zone of highest temperature to a relatively restricted region within and adjacent the discharge end of the kiln by projecting the fuel into the chamber in the form of a jet so directed that the fuel stream passes through the chamber along a circuitous path such that ignition of the fuel particles entering the chamber is brought about and combustion is maintained by radiant heat from the ignited fuel particles and also by radiant heat given off by the hot discharging material.

2. The method of burning fuel for heating non-combustible material in a kiln having an

inlet end for the material to be treated and a discharge end, and a primary combustion chamber in direct communication with the discharge end, which comprises passing the material discharging from the kiln through the chamber, admitting air into the chamber and during such admission raising the temperature of the air by heat radiated from the discharging material, projecting a jet of fuel of low volatile content into the chamber at an angle to the longitudinal axis of the kiln, and bringing about ignition of the entering fuel and assisting the maintenance of combustion thereof by causing the fuel stream to pass from its point of admission into the chamber to its point of admission into the kiln along a circuitous path such that the entering fuel stream receives heat radiated by the ignited portion thereof and also given off by discharging material.

3. The method of burning fuel for heating non-combustible material in a kiln having an inlet end for the material to be treated and a discharge end, and a primary combustion chamber in direct communication with the discharge end, which comprises passing the material discharging from the kiln through the chamber, projecting a jet of pulverulent fuel of low volatile content into the chamber at an angle to cause the fuel stream to flow through the chamber along a circuitous path in which the stream turns upon itself in proximity to the discharging material and in contact therewith and thus bringing about ignition of the entering fuel and assisting the maintenance of combustion thereof by heat given off by the ignited portion of the fuel stream and by the discharging material, and admitting air to the combustion chamber in proximity to the point at which the fuel stream turns upon itself.

4. In a method of burning fuel for heating non-combustible material in a kiln having an inlet end for the material to be treated and a discharge end, and a primary combustion chamber in direct communication with the discharge end, the steps of burning pulverulent fuel of low volatile content partly in the combustion chamber and partly in the kiln, and confining the zone of highest temperature to a relatively restricted region within and adjacent the discharge end of the kiln by projecting the fuel into the chamber in the form of two jets diffusing into each other, one of these jets being projected into the combustion chamber directly toward the discharge end of the kiln and the other being so directed into the combustion chamber that its fuel stream turns upon itself within the chamber in such manner that the entering portion of the fuel stream in both jets receives heat radiated from the ignited portion of the second jet.

5. In a method of burning fuel for heating non-combustible material in a kiln hav-

- ing an inlet end for the material to be treated and a discharge end, and a primary combustion chamber in direct communication with the discharge end, the steps of projecting a jet of fuel of low volatile content into the combustion chamber in such manner as to pass for only a portion of its path within such chamber immediately prior to its entry into the kiln in countercurrent to and in contact with the material discharging from the kiln, and projecting a second jet of said fuel through said combustion chamber directly toward the discharge end of the kiln and in such manner as to diffuse into the first jet at points within that portion of the latter's path within the combustion chamber in which it moves countercurrent to the material being discharged from the kiln.
6. In a method of burning fuel for heating non-combustible material in a kiln having an inlet end for the material to be treated and a discharge end, and a primary combustion chamber in direct communication with the discharge end, the steps of projecting a jet of fuel of low volatile content into the primary combustion chamber downwardly and causing the fuel so admitted to pass from its point of admission into the chamber to its point of admission into the kiln along a circuitous path, projecting a second jet of fuel of low volatile content into the chamber to diffuse into the first, the ignition and maintenance of combustion of the fuel in both jets being brought about in part by heat radiated from the ignited portion of the first jet, passing the material discharging from the kiln through the primary combustion chamber, and admitting the major portion of the air required to support combustion to the chamber in proximity to the said discharging material, whereby the air is preheated by heat radiated from the material.
7. In a method of burning fuel for heating non-combustible material in a kiln having an inlet end for the material to be treated and a discharge end, and a primary combustion chamber in direct communication with the discharge end, the steps of projecting a jet of pulverulent fuel of low volatile content downwardly into the primary combustion chamber to flow therethrough along a circuitous path to enter the discharge end of the kiln, projecting a pair of jets of said fuel at an angle to and out of alignment with the first jet, the said first jet being so projected that the unignited fuel entering the chamber in all three jets is ignited and its combustion maintained in part by heat radiated from the ignited portion of the first jet, passing the material discharging from the kiln through the chamber in proximity to portions of the several jets so that heat given off by the discharging material is in part absorbed by the entering fuel intro-
- duced into the chamber in the several jets, and admitting air into the chamber for supporting combustion therein in proximity to the discharging material, whereby the temperature of the air is raised prior to its mingling with the fuel.
8. The combination of an elongated rotary kiln adapted to convey material therealong by its rotation and having an inlet end for the introduction of the material to be heated and an outlet end through which the material is discharged, a primary combustion chamber having an opening in one wall through which the chamber is in direct communication with the kiln, the material discharging from the kiln passing through the opening into the chamber, means for projecting a jet of pulverulent fuel and air downwardly into the chamber, a flat elongated discharge opening in the wall of the chamber opposite to that through which the material enters the chamber, this opening permitting the entrance of air for combustion into the chamber over the surface of the discharging material to be heated thereby, and means in the bottom of the chamber for bringing about movement of the material from its point of entrance into the chamber and out of the discharge opening.
9. The combination of a rotary kiln adapted to convey material therealong by its rotation from an inlet end to a discharge end, a primary combustion chamber through one wall of which direct communication is provided with the discharge end of the kiln, means disposed in the lower end of the combustion chamber for conducting the material discharged from the kiln across the chamber and out through an opening in the wall opposite to that through which the material enters, means for projecting a jet of fuel vertically downwardly into the combustion chamber, and means for admitting regulating quantities of air into the combustion chamber in counterflow to the discharging material and over the surface thereof, whereby the air is preheated by the radiant heat from the said material.
10. The combination of a rotary kiln having an inlet end and a discharge end, this kiln being adapted to convey material from one end to the other by its rotation, a primary combustion chamber into which the discharge end of the kiln projects, means in the bottom of the chamber for conducting material discharging from the kiln out of the chamber, a nozzle for projecting a stream of fuel downwardly into the chamber, this nozzle being disposed at a distance from the end of the kiln, whereby the stream from the nozzle flows through the chamber and into the kiln along a circuitous path, a portion of which is in proximity to the material passing through the chamber, and a pair of nozzles for projecting jets of fuel into the chamber in sub-

stantial alignment with the discharge end of the kiln, these nozzles projecting jets which diffuse into the jet issuing from the first nozzle adjacent the discharge end of the 5 kiln.

In testimony whereof I affix my signature.
